DIESEL-TYPE ENGINE FOR TOY AIRCRAFT

Kenneth O. Woodruff, Englewood, and Robert L. Krier, Walsenburg, Colo.

Application October 21, 1946, Serial No. 704,604

3 Claims. (Cl. 123—73)

1

The present invention relates to a single cylinder diesel-type engine for toy aircraft. It has to do particularly, although not exclusively, with a single cylinder air-cooled diesel-type engine of extremely small size and of extremely light weight capable of propelling a toy or miniature aircraft, in which the engine is of the combustion-ignition type having no electric sparking arrangement. The principle could, of course, be used also with a multi-cylinder engine.

One of the objects of the present invention is to provide an engine of the foregoing character having a novel arrangement of parts, as well as a minimum number of parts, whereby to provide a compact engine structure of relatively small size and extremely light weight which is capable of being manufactured at relatively low cost, and one which will turn up at a maximum number of R. P. M.'s.

A further object of the present invention is to provide novel air intake-adjustment and adjustment-maintaining means for an engine of the foregoing character; it being another and important object of the invention to provide new and novel means for varying the displacement of the engine cylinder above the reciprocable piston located therein.

Another and important object of the present invention is to provide an efficient, compact, and light weight engine of the foregoing character which operates on the diesel principle and which is of the combustion-ignition type and therefore does not employ any sparking arrangement.

The foregoing and other objects and advantages of the present invention will be apparent from the following description and appended claims when considered in connection with the accompanying drawings forming a part of this specification, wherein like reference characters designate corresponding parts in the several views.

In said drawings:

Fig. 1 is a longitudinal vertical sectional view through an engine embodying the present invention.

Fig. 2 is a fragmentary elevational view taken substantially along the line 2—2 of Fig. 1, looking in the direction of the arrows; and

Fig. 3 is a fragmentary transverse vertical sectional view taken substantially along the line 3—3 of Fig. 1, looking in the direction of the arrows.

Before explaining in detail the present invention it is to be understood that the invention is not limited in its application to the details of

construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring now particularly to the drawings, the diesel-type engine of the present invention comprises a cylinder 10 mounted upon a crank case, shown as a whole at 11, the crank case, as shown, comprising sections 12 and 13 which are threaded together at 14. One end of the crank case is provided with a removable cap or cover 15 having an opening therein to permit access to a drain or inspection plug 16. The section 13 of the crank case comprises a vertical wall 17 having a right angularly and horizontally disposed tubular projecting portion 18 which carries a bearing for a crank shaft or propeller shaft, shown as a whole at 19. The wall 17 of the crank case carries a bronze bushing or bearing sleeve 20 for the crank shaft.

Attached to the section 13 of the crank case and extending outwardly in line therewith is a fuel tank 21 having an outer closure wall or disk 22 which, as shown, is threaded at 23 onto the portion 18 of the crank case. A breather plug or venting member 24 is, as shown, threaded into the wall of the fuel tank.

The crank shaft 19 has a reduced portion 19a which carries a propeller 25 and an outer threaded end portion 19b which receives a nut 26 to hold said propeller rigidly into engagement with the rotatable spacer ring or disk 27 which is disposed between the propeller 25 and the end wall 18. The outer end of the crank shaft or propeller shaft carries a streamlined spinner or cap member 28 which is recessed at 29 to receive the nut 26 and which is internally threaded at 30 to engage the threaded end 19b of the shaft. The spinner is preferably formed from plastic so as to reduce the weight of the engine assembly.

The inner end of the crank shaft 19 is connected, through a connecting rod 31, to a piston 32 which reciprocates in a liner or sleeve 33 which is pressed into the cylinder 10. The sleeve or liner 33 is spaced from the wall 10a of the cylinder to provide an intake or induction passage 34 communicating with an intake port 35 formed in the liner, see Fig. 1. The liner is also provided with a pair of preferably opposed exhaust ports 36 (one such being shown in Figs. 1 and 2) which

ports are in communication with outwardly projecting and preferably oppositely disposed exhaust pipes or passageways 37 which, as shown in Fig. 2, form an integral part of the walls of the cylinder 10. The upper portion of the walls of the cylinder 10 is threaded at 38 and is preferably shaped to provide an annular shoulder 39, Figs. 1 and 2.

The cylinder 10 is provided with an adjustable cylinder head, shown as a whole at 40, the head being provided with an annular groove 41 in its under side to receive the upper end of the sleeve or liner 33. The cylinder head 40 is provided with a series or plurality of heat dissipating and thus cooling fins 42 and has a cylinder head operating or manipulating member 43 having finger gripping pieces or extensions 43a, which member is pressed into a socket formed in the head 40 and which is disposed entirely externally of the cylinder and head. The cylinder head 40 has a skirt portion 44 which is internally threaded to engage the threads 38 of the upper portions of the cylinder walls. Thus, by turning the head in either direction by means of the actuating means 43, 43a, the displacement of the cylinder may be varied to thus vary, i. e. change, the size or area of the combined compression and explosion space within the cylinder above the piston 32.

The mixture of fuel and air, providing the combustible mixture for operating the combustion-ignition type engine of the present invention, are both preferably admitted to the engine cylinder through the crank case thereof. To provide means for admitting air, the section 13 of the crank case is extended upwardly at 45 and is provided with an aperture or opening 46 formed therein. A tubular sleeve-like member 47 having a head 48 and a notched periphery 49 is telescoped within the extension 45 and has an opening or aperture 50 formed therein which is adapted to register with the opening or port 46, see Fig. 1. It will be understood that by rotating the member 47, the size of the opening provided by the aligned ports 46 and 50 may be varied to control or regulate the amount of air admitted to the engine. To maintain the parts in their proper adjusted positions, a spring-like finger 51 is provided and is carried by the member or extension 45 to engage in the notches 49 of the cap member.

As seen clearly in Fig. 1, the crank shaft 19 is provided with a port or opening 19a and with a bore or hollowed-out portion 19b which together, provide a passageway for air entering through the openings 46, 50 to be drawn into the cylinder through the passageway 34 and inlet port 35, by suction created upon the reciprocation of piston 32. By virtue of this same suction, fuel within the fuel tank 21 will be sucked through a substantially U-shaped pipe or tube 52, whose upper end cooperates with a nipple 53, and will pass into the space 100 and be mixed therein with air. From this space it passes through port 19a, bore 19b into the crank case and thence will be drawn upwardly through the passageway 34 and port 35 into the cylinder above the piston 32.

It will be understood that the proper amount of fuel to air may be controlled or regulated to the desired proportions or mixture by virtue of the diameter of the pipe or tube 52, the bore of the nipple 53, and the size of the air intake opening provided by the apertures 46 and 50, so that the proper and desirable mixture may be provided.

It will be understood that as the cylinder head 40 is adjusted downwardly relative to the fixed cylinder 10, the displacement of the cylinder will be reduced, whereas the adjustment of the cylinder head upwardly, or away from the piston 32, will increase the displacement of the cylinder. It will also be understood that the greatest compression is obtained when the displacement is reduced, that is when the cylinder head 40 is in its lowermost position. In this position, with the air intake opening set properly, the propeller 25 is spun rapidly to create suction within the engine. Such suction draws into the cylinder the proper combustible mixture, which is compressed and fired by the combustion-ignition principle to start the engine in operation. After the engine has once been started and is in operation, the cylinder head 40 may be adjusted upwardly or away from the piston 32 to increase the displacement to approximately four (4) cubic centimeters for normal operation. With this setting, the improved engines of the present invention will develop up to approximately 5,000 R. P. M.

The entire novel engine structure of the present invention may be quickly and readily assembled or disassembled and will produce the necessary power for propelling miniature or toy aircraft on relatively long sustained flights.

The various parts making up the present novel engine structure are formed from material which is best suited to the particular design or part, some of the parts being machined from hard aluminum whereas others, such as the piston 32 and cylinder head 40, are preferably formed from steel. The spacer ring or disk 27 may be formed either from steel or aluminum and, as stated above, the spinner 28 is preferably formed from plastic although, if desired, it may be formed from a block of hard aluminum, or similar light weight material.

Having thus described the invention what is claimed is:

1. A two-stroke cycle internal combustion engine of the compression ignition type for use in miniature aircraft comprising a crank case, a hollow crank shaft projecting into the crank case, means for passing a combustible fuel-air mixture into the crank case through the crank shaft, a cylinder on the crank case having an inlet and an exhaust port but otherwise imperforate, a piston reciprocal in the cylinder to successively seal and open said ports, a connecting rod connecting the piston to the crank shaft, a solid imperforate cylinder head having an integral thickened central portion projecting downwardly into the cylinder in sealing engagement therewith and a skirt portion threadedly engaging the outer portion of said cylinder for axial adjustment of the cylinder head, whereby the compression ratio and therefore the ignition timing of the engine may be varied by axial movement of the cylinder head, the skirt portion of said axially adjustable head having a series of heat dissipating fins disposed on the exterior surface thereof.

2. A two-stroke cycle internal combustion engine of the compression ignition type for use in miniature aircraft comprising a crank case, a fuel tank concentric with the crank case, a hollow crank shaft extending through the fuel tank into the crank case, an air horn extending inwardly into communication with a port formed in a wall of the crank case for drawing a fuel-air mixture through the crank shaft into the

crank case, a fuel nozzle in the air horn, a tube in the fuel tank connecting the inner end of the fuel nozzle with the lower portion of the fuel tank, an adjustable means for varying the quantity of air drawn through the air horn, a cylinder on the crank case imperforate except for inlet and exhaust openings, the inlet opening communicating with the crank case, a piston reciprocal in the cylinder, a connecting rod connecting the piston and the crank shaft, and means for adjusting the ignition timing and compression ratio of the engine including an imperforate cylinder head sealing the top of the cylinder, said cylinder head having a groove for slidably receiving the upper end of the cylinder and an external skirt threadedly engaging the external portion of the cylinder.

3. A two-stroke cycle internal combustion engine of the compression ignition type for use in miniature aircraft comprising a crank case, a fuel tank concentric with the crank case, a hollow crank shaft extending through the fuel tank into the crank case, means including a fuel nozzle extending inwardly into communication with an opening formed in a wall of the crank case for drawing a fuel-air mixture through the crank shaft into the crank case, conduit means in the fuel tank connecting the fuel nozzle with the fuel tank, means for controlling the quantity of air drawn through the crank shaft, a cylinder on the crank case imperforate except for inlet and exhaust openings, the inlet opening communicating with the crank case, a piston reciprocal

in the cylinder, a connecting rod connecting the piston and the crank shaft, and means for adjusting the ignition timing and compression ratio of the two-stroke cycle internal combustion engine, said last-named means including an imperforate thickened cylinder head sealing the top of the cylinder, said imperforate thickened cylinder head having a groove for slidably receiving the upper end portion of the cylinder and an external cooling fin-carrying skirt threadedly engaging the external portion of the cylinder.
